UNITED STATES PATENT OFFICE

159,107

RAILWAY OBSERVATION CAR

Clifford Brooks Stevens, Milwaukee, Wis.

Application February 4, 1949, Serial No. 675

Term of patent 14 years

(Cl. D66—1)

To all whom it may concern:

Be it known that I, Clifford Brooks Stevens, a citizen of the United States of America, residing at Milwaukee, in the county of Milwaukee and State of Wisconsin, have invented a new, original, and ornamental Design for Railway Observation Car, of which the following is a specification, reference being had to the accompanying drawings, forming part thereof.

Figure 1 is a perspective view of a railway observation car, showing my new design;

Figure 2 is a rear end elevation thereof;

Figure 3 is a plan view of the rear portion of the car; and

Figure 4 is a side elevational view of the side of the car opposite that shown in Figure 1, but showing only the rear portion of the car.

The dominant feature of my design resides in the portion shown in full lines.

I claim:

The ornamental design for a railway observation car, substantially as shown and described.

CLIFFORD BROOKS STEVENS.
